UNITED STATES PATENT OFFICE.

LÉOPOLD JACQUES GAUTREAU, OF PARIS, FRANCE.

BURNER FOR LIQUID FUEL.

1,145,362.

Specification of Letters Patent.

Patented July 6, 1915.

Application filed October 31, 1911. Serial No. 657,743.

To all whom it may concern:

Be it known that I, LÉOPOLD JACQUES GAUTREAU, citizen of France, residing at 2 Rue Emile Deschanel, Paris, in the Republic of France, have invented new and useful Improvements in Burners for Liquid Fuel, of which the following is a specification.

This invention relates to burners consuming liquid fuel, and has for object improved burners which may be adapted for heating or illuminating and be of the upright, inverted, or inclined type.

In the accompanying drawings which are by way of example only, Figure 1 is a vertical section of an improved burner of the upright type for incandescent illumination. Fig. 2 is a horizontal section thereof. Fig. 3 shows an improved burner of the inverted type. Fig. 4 is a section along the line I—K in Fig. 3.

The burner illustrated in Figs. 1 and 2 comprises a tube 1 through which the fuel is supplied; this tube is open at both ends and one end is in communication with the fuel reservoir or supply pipe and the other with the interior of the vaporizer or heater 2. This vaporizer or heater 2 consists in an annular tube provided with two holes arranged at diametrically opposite points. In 30 said holes are respectively secured the inlet tube 1 and an outlet tube 3.

The vaporizer 2 communicates through the tube 3 with a socket 4 in which is fixed an ejector member 5 containing an axial orifice 6 of dimensions determined by the intensity of the light or heat which it is desired to obtain. The orifice 6 leads into the interior of a tube 7 provided near the ejector member with openings 8 and extending at 40 the top into a mixing tube 12 provided near its lower end with holes 9. A perforated disk or piece of metal gauze 10, held in place by a ring 11 or otherwise is located at the side of the holes away from the ejector 5. A funnel 12^a provided at the top with a perforated disk or piece of metal gauze 14 is in communication with the interior of the tube 12 through the holes of 10. A cup 15 near the bottom of the apparatus may contain a certain quantity of fuel. For concentrating on the heater or vaporizer 2 the heat of the flames escaping from the holes 9, the heater or vaporizer is provided with a cap or cover 16 which extends closely around the central tube 12 whereby the heated gases are prevented to rise along

said tube and are directed to the annular heater 2. Said cover 16 is bent downwardly at its edge around the vaporizer 2 so as to inclose the same in a heating chamber open at the bottom only in which the heating flames are fully concentrated and well protected against accidental extinction.

The manner of working is as follows: A certain quantity of alcohol or other fuel is 65 poured into the cup 15 and then ignited. The flames produced heat the vaporizer 2 and by conductivity the tubes 1 and 3 the socket 4 and the ejector 5. When the vaporizer 2 is sufficiently warm the fuel is 70 allowed to pass into the tube 1 and on contact with the heated walls of the vaporizer this fuel is heated and volatilized and then passes into the tube 3 from which it is conducted to the socket 4 whence it issues 75 through the orifice 6 of the ejector 5. The fuel escaping into the tube 7 draws in through the orifice 8 a certain quantity of air or other diluent. The combustible mixture then reaches the perforated disk 10 80 where a portion of the mixture owing to the resistance offered by the disk 10 passes out through the holes 9 and catches fire outside the tube 7, since it meets there the flames produced by the fuel in the cup 15; the rest 85 of the mixture passes into the funnel 12 and issues to the atmosphere where it is ignited and where in the case of an illuminating jet, it comes into contact with a suitable mantle which it raises to incandescence. 90 The heat produced by the combustion of the mixture issuing through the holes 9 is sufficient to maintain the vaporizer or heater 2 at a suitable temperature during the whole time of operation. The number and dimension of the holes 9 are such that the desired quantity of heat is obtained, this depending on the fuel employed. In this manner it is not necessary to supply fuel to the cup while the burner is in use, the cup being for 100 starting purposes only. The temperature required for starting may be produced either by the fuel contained in the cup or by any other source of heat. To extinguish the burner it is only necessary to cut off the 105 fuel supply in the tube 1.

Figs. 3 and 4 relate to a construction of burner of the inverted type which is substantially similar to the burner of the upright type shown in Figs. 1 and 2.

8 denotes horizontal tubes for the air supply.

Instead of the heater or vaporizer being formed by a torus separate from the tubes 1 and 3, the three parts may be in one piece and formed by a single tube suitably bent 5 to shape.

The improved type of burner will be used as a rule in an upright position but it may also be used in an inclined or horizontal position. It is then only necessary to modify 10 the position of the starting cup so that it remains horizontal.

The burners described may also be used for heating purposes by substituting a heating burner of any type for the illuminating 15 burner shown, no other change being necessary.

Having now described my invention, what I claim as new and desire to secure by Letters Patent is:

20 A burner of the character specified, embodying therein an annular vaporizer, a perforated mixing tube concentric with and surrounded by said vaporizer, a perforated duct secured to said mixing tube, said perfor-

ated duct being removably screwed upon 25 an injector supporting piece having an injector at one end thereof, a fuel supply tube having one end opening into said vaporizer and at its opposite end in communication with a source of fuel supply, an outlet tube 30 having one end opening into said vaporizer diametrically opposite the point at which the fuel supply tube opens into said vaporizer, the other end of said outlet tube being curved, said end carrying the injector supporting piece and having an orifice in open communication with the injector, and a cap 35 closely embracing said mixing tube and having its periphery bent over and conforming to the contour of said vaporizer.

40 In testimony whereof I have signed my name to this specification in the presence of two subscribing witnesses.

LÉOPOLD JACQUES GAUTREAU.
